AIR CONDITIONING SYSTEM

Hans Byland, Winterthur, Switzerland, assignor
to Sulzer Frères, Société Anonyme, Winterthur,
Switzerland

Application April 2, 1936, Serial No. 72,376
In Switzerland April 8, 1935

2 Claims. (Cl. 62—129)

This invention relates to an air conditioning system, more particularly to such a system in which the moisture content of the air is controlled by the addition of air dried in a drying apparatus and the temperature of the air is controlled by providing a cooling surface in the room which is to be supplied with conditioned air, the surface temperature of said cooling surface being equal to or higher than the temperature corresponding to the dew point of the air in said room.

An object of the present invention resides in the provision of an air conditioning system of the character described in the paragraph next above in which the work required for drying the air is reduced by reducing the amount of air which is supplied to the room or rooms which must be provided with conditioned air.

A further object of this invention resides in the provision of an air conditioning system in which the walls of the room or rooms to be supplied with conditioned air serve as cooling surface or in which the cooling surfaces are provided in an air channel which directly communicates with the room to be supplied with conditioned air.

Another object of the present invention is to provide an air conditioning system in which the cold for the cooling surfaces may be generated artificially and in which the blower which supplies the air, the refrigerator which generates the cold for drying the air, and the pump which transports the cooling agent for the cooling surfaces are all driven by the same motor.

Air conditioning for living rooms in hot and damp regions is particularly difficult because also the considerable heat must be removed which is caused by the radiation of the sun or introduced in another manner into the living rooms. If this heat is removed by ventilating, large amounts of air are required which must be dried before they are introduced into the rooms, for which a large amount of power is needed.

It is an object of the present invention to provide an air conditioning system which involves low first and low operating cost for maintaining temperature and moisture conditions of the air in rooms in territories having a hot and damp climate.

A further object of this invention is to provide an air conditioning system in which the surface temperature of the cooling surfaces is not lower than the temperature which corresponds to the dew point of the air in the rooms to be conditioned and in which, therefore, the

cold for cooling said surfaces need not be generated artificially and in which the capacity of the refrigerating plant can be small.

Another object of this invention is the provision of an air conditioning system in which parts of the walls of the rooms to be conditioned such as the ceiling and/or the side walls serve as cooling surfaces, whereby, due to the great size of these surfaces, condensation of moisture is avoided even if said walls are cooled by a cooling agent of very low temperature.

Further and other objects of the present invention will be hereinafter set forth in the accompanying specification and claims and shown in the drawing which, by way of illustration, show what I now consider to be a preferred embodiment of my invention.

In the drawing:

Fig. 1 is a diagrammatic layout of a plant according to the present invention. 20

Fig. 2 is a sectional view of a modification of a detail of the present invention.

Fig. 3 is a diagrammatic layout of a modified plant according to the present invention.

Fig. 4 is a diagrammatic layout of another modification of a plant according to the present invention. 25

Like parts are designated by like numerals in all figures of the drawing.

Referring more particularly to Fig. 1 of the drawing, blower 3 draws atmospheric air through intake 7 and duct 8 and blows it through conduit 9 into drier 10 from which it enters the air main 11. Air duct 12 is branched off said main 11 and terminates in room 14 which is to be supplied with conditioned air. A valve or damper 13 is provided in duct 12 for adjusting the amount of air supplied to room 14. Old air may leave room 14 through untight windows and doors or a special exhaust duct may be provided which is not shown. 30 35 40

4 represents a compressor which delivers a compressed cooling agent, for example, ammonia through conduit 15 into condenser coil 16 which is located in container 17; at the upper end of 45 condenser 16 an expansion valve 18 is provided. To valve 18, the evaporator coil 19 is connected which is located within apparatus 10 and terminates into the suction conduit 20 of compressor 4, the output of which can be controlled by control means 21 provided in conduit 20. 50

Through suction conduit 22, pump 5 draws cold ground water and delivers it through pressure conduit 23 into cold water main 26. Conduit 24 is branched off conduit 23 and conducts 55

water into container 17. The amount of water conducted through conduit 24 is controlled by valve 25 provided in said conduit. Conduit 27 takes the water from water main 26 into the 5 cooling systems 28, 29, and 30 which are built into the upper parts of the walls and into the ceiling of room 14, which parts and ceiling serve as cooling surfaces for temperature conditioning the air in the room. The amount of cold water 10 supplied to systems 28, 29, and 30 can be controlled by manipulating valve 31 in conduit 27. The cooling tube systems 28, 29, 30 may be arranged in series with respect to the flow of the water as shown, or they may be arranged in 15 parallel with respect to the flow of the cooling water. The cooling tube systems as well as container 17 are connected with discharge pipe 33 by means of conduits 32, 32', and 32''.

Blower 3, compressor 4, and water pump 5 20 are all connected to and operated by electric motor 6.

The plant operates as follows: if in room 14 the air temperature should be 82.4° F. and the moisture content be 55%, the amount of vapor 25 is 91 grains per pound of air and the dew point of this air is at 64.4° F. The moisture content of the air in room 14 is controlled by the addition of artificially dried air coming from conduit 12, which latter air absorbs part of the moisture 30 of the air in room 14. The air coming through intake 7 from the outside and having a high moisture content is cooled in apparatus 10 to a temperature which may be much below 64° F. in order 35 to obtain a great drying effect and to reduce the amount of dry air required for drying the air in room 14 and to thereby reduce the work required from blower 3.

The drying of the air takes place as follows: the cold carrier which is compressed in compressor 4 is condensed in condenser 16 by means 40 of the cooling water entering container 17 through and being controlled by valve 25; the liquefied cooling agent is then expanded in expansion valve 18 to the suction pressure of compressor 4, which pressure prevails in evaporator 19. The output of compressor 4 is adjusted 45 by valve 21 in such manner that the damp air entering apparatus 10 is cooled to the desired temperature by evaporator 19 which consists of one or more tube coils. Moisture contained in 50 the air is thereby condensed and the condensate removed from apparatus 10 through the drain 34. The air treated in this manner absorbs, at the temperature in room 14 of 82.4° F., a considerable amount of moisture without exceeding a 55 moisture content of 55%.

The temperature of the air in room 14 is controlled by the cooling surfaces of the side walls and the ceiling, the surface temperature of which 60 is not lower than the temperature corresponding to the dew point of the air in the room. In the example which has been developed in the paragraphs next above, this surface temperature is at least 64.4° F. and is maintained by the 65 flow of cold water through tube systems 28, 29, 30. The heat of the air is transmitted to the cooling surfaces not only by convection and conduction but also by radiation to said cooling surfaces. Heat transmission by radiation is particularly facilitated by building the cooling surfaces into the walls of the room and the large area of the thus obtained cooling surfaces which directly face the room to be cooled. The ar-

rangement of the cooling surfaces in the upper part of room 14 causes an advantageous circulation of the air.

In the modification according to Fig. 2, the tube system 28' is built within channel 35 so that 5 not only wall 36, which is a wall of room 14, due to the cooling tube system suspended thereon, serves as cooling surface for room 14, but also channel 35 which communicates with both ends with room 14 and aids in causing additional cooling and circulation of the air in said room.

If water of a sufficiently low temperature is available, for example from a well, the parts 4, 15, 16, 17, 18, 19, 20, and 21 may be dispensed with and apparatus 10 be operated with said 15 cold water. Such an arrangement is diagrammatically shown in Fig. 3. The cold water is conducted to apparatus 10' through conduit 24' and its amount is controlled by valve 25'; it comes in direct contact with the air in apparatus 10' and water and condensed moisture from the air leaves apparatus 10' through outlet 34. In this manner the air is also cleansed.

Instead of using cold water as cooling agent for the tube systems 28 to 30, the cooling agent 25 prepared by pump 4 and condenser 16, for example the vapor emerging from evaporator 19 may be used. Such an arrangement is diagrammatically shown in Fig. 4. The vapor emerging from coil or coils 19 is conducted into main 26 30 and therefrom into the cooling tube systems. It returns therefrom into pump 4 to be once more compressed and condensed. Pump 5 then serves only for circulating cold ground water through condenser 17.

It is obvious that one air drier may serve for supplying dried air to a plurality of rooms, or individual driers may be provided for individual rooms and such driers be located within or outside of the rooms to be supplied with dried air. 40

While I believe the above described embodiments of my invention to be preferred embodiments, I wish it to be understood that I do not desire to be limited to the exact details of process, design and construction shown and described, for 45 obvious modifications will occur to a person skilled in the art.

What is claimed is:

1. An air conditioning plant for a room comprising an air drier located outside of said room, 50 air transport means transporting fresh outside air through said drier into said room for drying the air in said room by adding dry air thereto, refrigerating means providing an operating agent for said drier, cooling surfaces integral with the walls of said room other transport means transporting a cooling agent through said cooling surfaces, and a motor connected to and driving said first mentioned as well as said second and third mentioned means.

2. An air conditioning system for a room having walls, said system comprising cooling means which are integral with said walls, an air drier located outside of said room for drying fresh outside air and delivering it into said room for 65 drying the air therein by the addition of dry air, a refrigerator providing a cooling agent as an operating medium for said system and for said drier, and circulating means circulating said cooling agent through said refrigerator, through said drier for operating said drier and through 70 said cooling means.

HANS BYLAND.
